UNITED STATES PATENT OFFICE

2,517,877

NOZZLE AND TIP FOR BURNING AND
WELDING TORCHES

Alva K. Hinchman, Bryn Mawr, Pa.

Original application March 31, 1944, Serial No. 528,987, now Patent No. 2,474,673, dated June 28, 1949. Divided and this application May 26, 1949, Serial No. 55,408

4 Claims. (Cl. 158—27.4)

1

My invention relates to new and useful nozzles and tips for burning and welding torches and being a division from my application filed March 31, 1944, Serial No. 528,987, now become Patent Number 2,474,673, granted June 28, 1949.

An object of the present invention is to provide a collet regulator of novel construction for the bore of a burning and/or welding torch which regulator is moved towards the closed position by a pushing or thrust action of the regulator relative to the head section of the nozzle.

Another object of the invention is to simplify the construction of articles of the class specified whereby they will be exceedingly efficient in operation although relatively inexpensive in the cost of manufacture.

A further object of this invention is to provide a sectional nozzle in which each section may be drilled separately to facilitate manufacture and reduce costs.

With the above and other objects in view this invention consists of the details of construction and combination of elements hereinafter set forth and then designated by the claims.

In order that those skilled in the art to which this invention appertains may understand how to make and use the same I will describe its construction in detail referring by numerals to the accompanying drawing forming a part hereof, in which:

Fig. 1 is a longitudinal sectional view of the nozzle shell with regulator elements in elevation.

Fig. 2 is a bottom or inner end view thereof.

Fig. 3 is a longitudinal sectional view of the regulator collet.

Fig. 4 is a similar view of the adjusting member.

Fig. 5 is an upper or outer end view of the regulator collet.

In carrying out my invention as herein embodied, 6 represents a two-piece or sectional nozzle for burning and welding torches, comprising a body or inner member or section 7 and a head or outer member or section 8, connected together by a threaded joint. This construction makes it easy to form the various types of bores, passageways, openings and recesses with short boring operations and likewise makes it easy to reach certain locations for countersinking, finishing and the like, thus facilitating the manufacture and reducing the cost thereof.

The nozzle body 7 is provided with a reduced externally threaded portion or shank 9 adapted to be screwed into a torch head, and a non-circular portion 10 for the reception of a wrench

2

or other tool. A bore 11 is formed in the body section 7 from end to end, including the shank, and said body section is internally threaded for a short distance at its inner end as indicated at 12.

An externally threaded neck 13 is formed at the inner end of the body section 7 and provides a shoulder 14 and said neck has a flat end to provide a flat seat 15. This neck 13 is projected into the threaded socket 16 at the inner end of the nozzle head section 8 for joining the two sections together with the shoulder 14 abutting the inner end of said head section 8 and the seat 15 engaging the shoulder 17, produced by the formation of the socket, to provide a gas tight joint. A bore 18 in the head section 8 runs from end to end of the said head section and is slightly larger than the bore 11 so as to expose a portion of the seat 15 within the bore 18 when the two sections are joined together. The outer end of said bore 18 terminates in a cone shaped or converging internal seat 19.

The outer end of said head section is externally threaded at 20 to receive a demountable tip 21 and the inner end of said head section has a non-circular portion 22 for the reception of a wrench or other tool.

The tip 21 is of non-circular configuration on the exterior whereby it may be readily rotated and is internally threaded for mounting and adjustment on the threaded end of the head section of a nozzle. This particular tip has a tapered hole 23 in the center of its top or end wall, and because of the shape of the hole 23 said tip 21 preferably is used with liquified gas, such as propane, butane and the like.

A regulator 24 includes two separate but co-acting elements, one a sleeve 25, Fig. 3, and the other an adjusting member 26, Fig. 4. The sleeve 25 has its upper or outer portion slit longitudinally as at 27 and provided with a cone shaped end 28 to fit the conical seat 19. The segments produced by the slits are contracted as the sleeve 25 is pushed outward and due to the inherent resiliency they will spring apart or expand as the sleeve is permitted to or actually is moved inward. The sleeve bore 29 runs completely through it from end to end.

The adjusting member 26 includes an externally threaded shank 30 and a knurled head 31 for readily screwing said shank in and out of the threaded portion of the bore 11 of the body section 7 for setting said adjusting member. After the desired setting has been obtained a lock nut 32 on the threaded shank is screwed down tight

against the seat 15. Now when the head and body sections of the nozzle are screwed together, the adjusting member 26 will engage the inner end of the sleeve and force the latter outwardly so that the conical end 28 will slide along the cone shaped seat 19 a predetermined distance which will regulate the size of the sleeve bore at its outer end.

The adjusting member 26 has a bore 33 running from end to end thereof to permit passage of gases or fluids through the nozzle.

Of course I do not wish to be limited to the exact details of construction herein shown and described as these may be varied within the scope of the appended claims without departing from the spirit of my invention.

Having described my invention what I claim as new and useful is:

1. A nozzle for gas burning apparatus comprising a head section provided with a bore therethrough from end to end thereof, a conical seat on the interior of the outer end of said head section, a socket at the inner end of said head section, a body section having a bore therethrough from end to end thereof and interiorly threaded at the inner end, a neck carried by said body section for engagement with the socket end of the head section to detachably connect said sections, a sleeve having a conical outer end to fit the conical seat and slit for a distance from said outer end longitudinally inwardly, a hollow adjusting member externally threaded and adjustably screwed into the inner end of the bore of the body section to contact the sleeve for pushing

the latter outwardly as the sections are connected together, and a lock nut on the adjusting member engaging the inner end of the body section.

5. 2. The nozzle of claim 1, wherein the outer end of the head section is threaded, in combination with a tip removably mounted on said threaded outer end.

3. The nozzle of claim 1, wherein the outer end of the head section is provided with means for attachment thereto of any one of a number of interchangeable tips, the mounted tip coacting with the terminal end of the conical portion of the sleeve.

15. 4. In a nozzle for gas burning apparatus including a body section and a head section detachably connected together and each having a bore therethrough from end to end thereof, said head section having a cone shaped seat on the interior of the outer end thereof, a regulator within said nozzle and comprising a sleeve having a cone shaped outer end to engage the seat and slit longitudinally inwardly a distance sufficient to produce several segments having an inherent 20 resiliency to normally separate them, and a hollow adjusting member threadededly connected to the body section for adjusting said member longitudinally, said member coacting with the sleeve to push the latter outwardly when the sections 25 are connected together and thereby contracting the segments.

ALVA K. HINCHMAN.
